UNITED STATES PATENT OFFICE.

ALBERT MORTIMER, OF CHICAGO, ILLINOIS.

MONEY TRAY FOR BANKERS AND THE LIKE.

Application filed November 8, 1924. Serial No. 748,725.

My invention relates to improvements in money trays for bankers and the like, and it consists in the combinations, constructions, and arrangements herein described and 5 claimed.

An object of my invention is to provide a money tray which is adapted to hold bills of various denominations and which has novel means for instantly conveying the 10 bills to a safe place in case the bank is suddenly robbed, this means being actuated by the closing of a switch of an electrical circuit.

A further object of my invention is to 15 provide a device of the type described in which a number of these trays are connected to each other, each having a push button switch and so arranged that all of them will be operated when any one of the push 20 buttons is closed. The push buttons may be disposed in various places around the room, such as on the desks of the paying and receiving tellers, and other like places.

A further object of my invention is to 25 provide a device of the type described which is extremely simple in construction, and which is thoroughly efficient for the purpose intended.

Other objects and advantages will appear 30 in the following specification, and the novel features of the invention will be particularly pointed out in the appended claim.

My invention is illustrated in the accompanying drawings forming part of this 35 application, in which—

Figure 1 is a vertical section through the device,

Figure 2 is a front elevation of the device,

Figure 3 is an enlarged detail view of a 40 portion of the device,

Figure 4 is a diagrammatic view showing a number of the devices, and

Figure 5 is a wiring diagram of one of 45 the circuits employed with the device.

In carrying out my invention I provide a tray 1 which is hinged at 2 to a U-shaped casing 3. The casing 3 has sides 4 and a front wall 5. The casing 3 is supported by 50 the floor 6 of the bank and is disposed directly above an opening 7 in the floor through which a conveyor or chute 8 extends. A funnel-shaped member 9 is disposed at the lower end of the casing 3 and communicates with the chute 8. In Figure 1 I have 55 shown the lower end of the chute 8 in com-

munication with a vault box 10. If desired, the chutes may be led to different boxes, as shown in Figure 1.

Bill containers 11 are disposed upon the 60 plate 1 and are adapted to hold the bills of various denominations which the banker uses. In this form of the drawing, I have shown the containers 11 as consisting of frames without bottoms. The bills therefore 65 will be supported by the tray 1. From this construction it will be apparent that when the tray 1 swings into the dotted line position shown in Figure 1, the trays, together with the bills, will be conveyed to the chute 70 8 and from there to the vault boxes.

Means for holding the tray in the full line position consists of two arms 12 which have inwardly extending portions 13 that are received in openings 14 and are disposed beneath the tray 1 so as to support the tray. The arms 12 are hinged at 15 and then extend inwardly into the box until their ends 16 almost abut each other. Figure 3 shows an enlarged detail of the construction of 80 the hinge 15. It shows how the hinge 15 is connected to the arm 12 by means of a sleeve 17.

Referring to Figure 5 it will be seen that the arms 12 are adapted to be moved or 85 swung about the hinges 15 by means of a lever 18. The lever 18 is pivoted at 19 to the wall 5 (see Figure 1). A magnet 20 is also carried by the wall 5 and is positioned beneath the lever 18 so as to swing 90 the lever when the magnet is energized, thus swinging the arms 12 about the hinges 15. When the magnet 20 is energized, it will swing the lever 18 in the direction of the arrow shown in Figure 5. This movement 95 will remove the portions 13 from the casing 3, thus allowing the tray 1 to swing into the dotted line position. In Figure 5 I have shown three of the devices connected to each other by means of wires, and switches. The 100 switches 21 are disposed on the front wall 5 of the device, where they may be readily pressed in case of danger. The circuit shows that a current will flow from the battery 22 or other source of current, to all of the magnets 20 when any one of the switches 21 is closed.

From the foregoing description of the various parts of the device, the operation thereof may be readily understood. In installing the devices, the casing 3 is placed 110 in the desired position and then the chute 8

is placed beneath the casing and leads to the vault or other place of safe keeping. If a number of the devices is used, a like number of chutes is employed.

5 In case of robbery, the person who is not endangered for the time being may close the switch 21 which is nearest him and thus actuate all of the devices so as to cause the money to fall into the vault boxes 10. It 10 will therefore be seen that the money is instantly conveyed to a place of safe keeping, thus preventing the robbery from taking place.

I claim:

15 A device of the type described comprising a casing having relatively small openings in the sides thereof, a tray hingedly secured to said casing for holding bills of

various denominations thereon, a plurality of bottomless compartments loosely mounted 20 upon said tray for separating the bills from each other and into their various positions, arms hingedly secured to the sides of said casing and provided with inwardly extending portions adapted to be received in the 25 openings for holding said tray in operative position, means for forcing said arms outwardly permitting the inwardly extending portions to release said tray, whereby said bottomless compartments will slide free 30 of said tray, the bills falling free of said compartments as soon as the compartments slide free of said tray, and a receptacle for receiving said bills.

ALBERT MORTIMER.
